ANTENNA MOUNTING MEMBER

Jack Grafman, Pasadena, Franklin D. Hurd, Los Angeles, and Walter L. Schott, Beverly Hills, Calif., assignors to Walter L. Schott Co., Los Angeles, Calif., a corporation of California

Application May 18, 1954, Serial No. 30,548

Term of patent 7 years

(Cl. D26—14)

FIG. 1.

FIG. 4.

FIG. 2.

FIG. 5.

FIG. 3.

To all whom it may concern:

Be it known that we, Jack Grafman, Franklin D. Hurd, and Walter L. Schott, all citizens of the United States and residents of Pasadena, Los Angeles, and Beverly Hills, respectively, county of Los Angeles, State of California, have invented a new, original, and ornamental Design for Antenna Mounting Member, of which the following is a specification, reference being had to the accompanying drawing, forming a part hereof, in which:

Fig. 1 is a front elevation of an antenna mounting member, showing our new design;

Fig. 2 is a plan view thereof;

Fig. 3 is a rear elevational view thereof;

Fig. 4 is an end elevational view thereof; and

Fig. 5 is a sectional view on line 5—5 of Fig. 2.

We claim:

The ornamental design for an antenna mounting member, substantially as shown.
